UNITED STATES PATENT OFFICE

CHARLES F. GOLDEN, OF DENVER, INDIANA

DRAFTING INSTRUMENT

Application filed February 1, 1930. Serial No. 425,329.

This invention relates to a drafting instrument, one of its objects being to provide a light, simple and compact instrument of this character which can be used accurately as a protractor, compass, T-square and vernier scale.

Another object is to provide an instrument formed of few parts including a protractor head and an arm which are detachably connected so that one can be used independently of the other.

A further object is to provide a protractor head with a pivot pin located at the center of the base line and in line with one edge of the arm, this pin being shiftable to engage the surface on which the instrument is mounted.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing the preferred form of the invention has been shown.

In said drawing,

Figure 1 is a plan view of the instrument.

Figure 2 is a section on line 2—2, Figure 1.

Figure 3 is an enlarged section on line 3—3, Figure 1.

Figure 4 is an enlarged section on line 4—4, Figure 1.

Figure 5 is a section on line 5—5, Figure 4.

Referring to the figures by characters of reference, 1 designates a semi-circular protractor head the arcuate outer edge of which is graduated to indicate degrees and fractions of degrees of a circle. The central graduation is indicated by the zero character "0", as shown at 2.

The straight edge 3 of the protractor head is graduated preferably in inches and fractions thereof in opposite directions from the center thereof and the center portion of this

edge is cut away to provide a clearance indicated at 4. The outer edge portions of the head 1 are pressed downwardly by beveling the head so that said head can thus lie flat on a supporting surface.

Fitted snugly beneath the head 1 at 90° to its straight edge 3 is a flat tongue 5 projecting from one end of an elongated vernier arm 6. The longitudinal edge portions of this arm are inclined downwardly so as to lie in the same plane with the edges of the head 1. These edges of the arm are graduated to indicate any desired units of lineal measure and any desired fractions thereof. The graduations are designated by numerals or the like as shown, for example, in Figure 1.

That end of the arm 6 which is offset and flattened to produce the tongue 5 is seated in a recess 7 formed in head 1 along the straight edge 3 and at one side of the cut-away portion 4 or clearance 4.

Secured to the tongue 5 are screw threaded studs 8 which extend through openings 9 in head 1 and are engaged by clamping nuts 10 which serve to bear on the head and hold tongue 5 and arm 6 fixed relative to the head.

Secured on the head 1 at one side of the clearance 4 is a small base plate 11 from which projects an upwardly extending bracket or arm 12 carrying an integral sleeve 13. The bore 14 in this sleeve has a pin 16 slidably mounted therein provided with a head 17 at one end. A portion of the pin is reduced annularly as at 15 to receive a set screw 18. A centering point 18 extends from that end of the pin remote from the head 17.

The outer or free end of arm 6 is obliquely disposed as indicated at 20 and is provided with suitable graduations for designating fractions of a degree in minutes or otherwise. One longitudinal edge of the arm is in alignment or substantial alignment with the zero graduation 2 and the point 19. In practice it has been found desirable to set back the longitudinal edge of the arm a distance equal to the thickness of a fine pencil point so that a line drawn along said edge will aline with the point 19 and the zero graduation 2.

It will be obvious that, by removing the nuts 10, studs 8 can be withdrawn from the

head 1 and it is thereby possible to use the head and the arm 6 independently of each other.

As has heretofore been stated this instrument can be used as a protractor, compass, T-square and vernier scale. Attention is directed to the novel arrangement of graduations on the protractor head. The outer series of graduations is arranged to aid in reading angles ranging from 0° to 90° east or west, north or south, and to facilitate measurement of the segments of circles. For example, should it be desired to lay out an azimuth of 350° it would be necessary first to anchor the pin 16 at the desired position on the base line with the arm 6 pointing north parallel to the base line. The 0° graduation will thus be in position on the line. The protractor head is then rotated in a clockwise direction as indicated by the arrow until the 90° graduation appears at the north meridian. The head is then further rotated in a clockwise direction at which time the intermediate set of graduations will indicate the readings from 90° upwards until the 270° graduation appears at the north meridian. Further rotation in a clockwise direction will bring the inner or third set of graduations into use for indicating the degrees ranging from 270° upwards until the 350° graduation appears at the south meridian. Thus speed, accuracy and convenience are assured to the user of this instrument.

When the parts are assembled as shown in Figure 1 the pivot pin becomes useful when the device is employed as a T-square, it being possible readily to swing the instrument about the pivotal point.

The protractor feature of the instrument is important. For example, should it be desired to produce an angle north 600 ft., 45 degrees 10 minutes east, the pivot point is positioned on the base line. The zero degree 2 at the south meridian is positioned in line with the edge of arm 6. The instrument is then swung about the pivot until the arm reaches a point which will cause the 45° graduation to appear at the south meridian. A mark is made at the first graduation on the outer end 20 of the arm 6. The arm is then turned until its straight edge coincides with the last mark made. A line is then drawn along the straight edge to the center.

By providing a set screw 18 which projects into groove 16 in pin 16 the sliding movement of the pin will be limited. By withdrawing the set screw from the groove the pin can be removed.

What is claimed is:

1. An instrument of the class described including a semi-circular protractor head having a zero graduation at the center of its arcuate edge, the straight edge of the head being cut away at its center to provide a clearance, an arm detachably connected to the

head and having a straight edge in line with the zero graduation and the center of the straight edge of the head, a bracket fixedly secured to the head and overhanging the clearance, and a centering pin carried by the bracket and extending through said clearance for engaging a supporting surface at a point in line with the zero graduation and the straight edge of the arm, said arm being removable from the head without disturbing the pin.

2. An instrument of the class described including a protractor head having its arcuate edge graduated to indicate all of the degrees of a circle, the zero graduations being located at the center of said edge, said head being semi-circular and having a straight graduated edge provided with a central clearance, a graduated arm extending from the straight edge of the head and having one edge substantially in line with the center of said straight edge and with the zero graduation, the straight edge of said arm being cut away to provide a clearance adapted to register with the clearance in the straight edge of the head, a bracket fixedly connected to the head and overlying the registering clearances, and a centering pin movably connected to the bracket and insertable into the clearances to engage a supporting surface at a point in line with the straight edge of the head, and means for detachably securing said arm to the head for removal without disturbing the pin and its bracket.

In testimony that I claim the foregoing as my own, I have hereto affixed my signature.
